LATCH MEANS FOR RETRACTABLE BALL PENS

Blanchard D. Smith, Atlanta, Ga., assignor to Scripto, Inc., Atlanta, Ga., a corporation of Georgia

Application December 14, 1953, Serial No. 398,121

2 Claims. (Cl. 120—42.03)

This invention relates in general to retractable ball pens of the type in which a ball point and reservoir unit is made retractable so that it may be alternatively withdrawn within the pen barrel when not in use or projected from the barrel for writing when desired, and in particular to an improved latch means for holding the ball point unit at projected position and releasing it for retraction as desired.

Briefly described, the latch mechanism of the present invention is characterized by a composite plunger member slidably assembled within a barrel housing formed with a fixed latch keeper, and arranged so that one component of the plunger member is manually operable for directing another component into engagement with the latch keeper at the projected position of the ball point unit, while the other component is made manually accessible for operation to release the latch keeper whenever engaged therewith. Also, the composite plunger member is arranged so that the component thereof engaging the latch keeper is maintained in such engagement under a pressure directed angularly with respect to the longitudinal axis of the pen barrel to provide a particularly secure latching engagement while at the same time leaving the latch means easily releasable.

These and other features of the present invention are described in detail below in connection with the accompanying drawings, in which:

Fig. 1 is an elevation, with portions in section, of a retractable ball pen incorporating a latch means arranged according to the present invention;

Fig. 2 is a transverse section taken substantially on the line 2—2 in Fig. 1; and

Fig. 3 is an enlarged view of the upper sectioned portion of Fig. 1 illustrating further the manner in which the latch means operates.

Referring now in detail to the drawings, the reference numeral 10 indicates generally a retractable ball pen embodying the present invention in a form incorporating a barrel housing formed by a tubular barrel 11 fitted at its rear end with an assembly sleeve 12 carrying a cover cap 13.

The tubular barrel 11 is preferably formed in accordance with the disclosure of copending application Serial No. 386,946 filed October 19, 1953, for slidably housing and laterally supporting an ink reservoir tube 14 formed of compressible plastic material and having a ball point element 15 fitted at the forward end thereof for projection to writing position through a forwardly tapering writing end of the tubular barrel 11 at which an inwardly facing annular shoulder 16 is arranged as a bottoming seat for the ball point element 15, all as disclosed at length in the above noted copending application. While this previously disclosed form for the tubular barrel 11 in relation to the ink tube 14 and ball point element 15 is preferred for use with the latch means of the present invention, any other generally comparable form of pen barrel and retractably housed ink tube and ball point element can be operated equally well by the latch means of this invention.

2

The assembly sleeve 12 has a portion thereof arranged, as indicated at 17, for threaded engagement within the rear end of the tubular barrel 11, which engagement renders the assembly sleeve 12 detachable from the tubular barrel 11 to provide for replacement of the ink tube 14 and ball point element 15 whenever required, as will appear more fully below. The forward end of the threaded assembly sleeve portion 17 terminates at an inwardly extending annular flange 18 which supports a bias spring 19 for the latch means. Rearwardly of the threaded portion 17, the assembly sleeve 12 is shouldered outwardly at 20, to a further tubular portion 21 of enlarged diameter. This enlarged tubular portion 21 has the cover cap 13 pressed in fixed relation thereon, and the cover cap 13 is in turn formed with a rear inwardly extending annular flange 22 so that the cover cap and assembly sleeve together form a housing for the latch means. The shouldered portion 20 of the assembly sleeve 12 may be employed further to grip an assembly ring portion 23 of a pocket clip 24 against the rear face of the barrel 11 and thereby secure the pocket clip 24 in place upon assembly with the barrel 11.

The latch means proper comprises a composite operating member having a plunger component 25 and a latch component 26. The plunger component 25 is formed with a rear manually accessible portion 27 projecting rearwardly as a push button through the annular flange 22 of the cover cap 13. At the base of this rear portion 27, the plunger component 25 is shouldered at 28 in opposed relation to the inner face of the cover cap flange 22, and abutment of the plunger component shoulder 28 at the inner face of the cover cap flange 22 defines the retracted position for the latch means. Below the abutment shoulder 28, the plunger component 25 has an intermediate portion 29 slidably fitting the cover cap 13; and below this intermediate portion 29, the plunger component 25 extends in reduced diameter to an abutment shoulder 30 for the bias spring 19, and then in further reduced diameter to a forwardly extending clutch portion 31 shaped to grip the rear end of the ink tube 14 for exerting endwise projecting pressure thereon and for carrying the ink tube 14 therewith to retracted position. In addition, the plunger component 25 is slotted intermediately of its length to provide a longitudinal recess 32 extending forwardly at one side thereof below the abutment shoulder 28 to a lateral channel 33 extending therethrough and forming a forwardly projecting fulcrum portion 34 therein.

The latch component 26 of the composite operating member is formed as a lever element nestable within the slotted portion of the plunger component 25. This lever element forming the latch component 26 has a lateral offset 35 at one end extending in the lateral plunger component channel 33 for lateral rocking or shifting 55 about the fulcrum portion 34, and an oppositely disposed lateral offset 36 at the other end for engaging a lateral aperture 37 arranged in the cover cap 13 as a keeper for the latch component 26 when the plunger component 25 is depressed to move the ink tube 14 and ball point element 15 to projected position.

At this projected position, the lateral latch offset 36 is moved to engage the lateral cover cap aperture 37 by the bias spring 19 acting at a hook shaped lip 38 formed on the extending end of the other lateral latch component offset 35 that is disposed within the lateral plunger component channel 33. In this way, the force of the bias spring 19 is exerted about the plunger component fulcrum portion 34 to maintain the latch component 26 always biased away from its nested position, while at the same time biasing the plunger component 25 rearwardly in the cover cap 13 to exert a pressure through the plunger component 25 directed angularly with respect to the longi-

tudinal axis of pen 10 for maintaining the latch component 26 engaged at the cover cap aperture 37.

The lateral latch offset 36 is proportioned to extend through the cover cap aperture 37 when engaged therewith, as indicated by the full line position shown in Figs. 1, 2 and 3, so that it becomes manually accessible upon such engagement for release whenever desired; release being effected simply by pressing the extending end of the lateral offset 36 inwardly of the cover cap 13 so that the latch component 26 assumes the broken line position shown in Fig. 3 at which it is nested with the plunger component 25 for retraction within the cover cap 13 under the force of bias spring 19.

The present invention has been described in detail above for purposes of illustration only and is not intended to be limited by this description or otherwise except as defined in the appended claims.

I claim:

1. A retractable ball pen latch means comprising, in combination with a tubular barrel and a ball point and reservoir unit slidably contained therein for retracted and projected positioning, an assembly sleeve removably mounted at the rear end of said tubular barrel together with a rear cover cap fixed on said assembly sleeve and a composite operating member slidably contained therein for positioning said ball point and reservoir unit, said operating member having a plunger component and a latch component carried thereon, said plunger component projecting forwardly as a clutch for releasably gripping said ball point and reservoir unit and rearwardly beyond said cover cap as an operating push button and being slotted intermediately of its length to provide a longitudinal recess extending forwardly at one side thereof to a channel extending laterally therethrough and forming a forwardly projecting fulcrum portion therein, said latch component being formed as a lever element nestable within the slotted portion of said plunger component and having a lateral offset at one end extending in said lateral channel for lateral rocking about said fulcrum portion and an oppositely disposed lateral offset at the other end, and a compression spring carried by said assembly sleeve in opposition to forward sliding of said operating member and to nesting rocking of said latch component, said cover cap having a lateral aperture therein forming a keeper for engaging said oppositely disposed offset upon forward sliding of said operating member to project said ball point and reservoir unit, and said op-

positely disposed offset being formed to extend through said cover cap aperture upon engagement therewith for manual release therefrom.

2. A retractable ball pen latch means comprising, in combination with a tubular barrel and a ball point and reservoir unit slidably contained therein for retracted and projected positioning, a composite operating member slidably contained at the rear end of said barrel for positioning said ball point and reservoir unit, said operating member having a plunger component and a latch component carried thereon, said plunger component extending forwardly within said barrel for exerting projecting pressure on said ball point and reservoir unit and rearwardly beyond said cover cap as an operating push button, and said plunger component being slotted intermediately of its length to provide a longitudinal recess extending forwardly at one side thereof to a channel extending laterally therethrough and forming a forwardly projecting fulcrum portion therein, said latch component being formed as a lever element nestable within the slotted portion of said plunger component and having a lateral offset at one end extending in said lateral channel for lateral rocking about said fulcrum portion and an oppositely disposed lateral offset at the other end, and a compression spring carried by said barrel in opposition to forward sliding of said operating member and to nesting rocking of said latch component, said barrel being formed for allowing lateral rocking of said latch component by said spring and for then engaging said oppositely disposed offset upon forward sliding of said operating member to project said ball point and reservoir unit.
